UNITED STATES PATENT OFFICE.

WILHELM EICHNER, OF CHARKOW, RUSSIA.

GRIPPING APPARATUS FOR AERIAL ROPEWAYS.

SPECIFICATION forming part of Letters Patent No. 740,830, dated October 6, 1903.

Application filed January 15, 1903. Serial No. 139,203. (No model.)

To all whom it may concern:

Be it known that I, WILHELM EICHNER, engineer, a subject of the German Emperor, residing at Charkow, Government of Charkow, 5 Empire of Russia, have invented new and useful Improvements in Gripping Apparatus for Aerial Ropeways, of which the following is a specification.

The present invention relates to a gripping apparatus for aerial traveling ropeways and belongs to that class of these apparatus in which the clamping action is effected by the weight of the load to be conveyed or the vessel containing this load. The characteristic 15 feature of the present gripping apparatus consists therein that the trolley-frame traveling on the fixed stationary cable or rail and carrying by means of a suspension-frame the said vessel or the load makes a slight oscillatory movement across to said stationary cable or rail in that point of time in which the gripping apparatus is to be opened, so that the load or the vessel containing the latter will be released from the traveling rope. 20 To accomplish this releasing effect, one of the gripping-jaws clamping the traveling rope between them is immediately or by means of a suitably-constructed hanger connected with the trolley-frame, while the other jaw is provided on or operated by a joint-piece connecting the trolley-frame with the suspension-frame, which latter carries the load immediately or by means of a conveying vessel. At the upper part or the top of the trolley-frame 25 there is provided a roller journaled on a vertically-arranged pivot, and in that point of time in which the releasing of the load or the vessel carrying the latter must take place this top roller is brought in contact with a straight or curved rail arranged horizontally 30 and in such a manner that the trolley-frame now traveling past this rail will receive the aforesaid crossly-directed oscillatory movement around the stationary supporting cable or rail. In consequence of this oscillatory 35 movement of the trolley-frame the load or its vessel is a little raised, whereby at same time both gripping-jaws are separated one from another as much as required to entirely free 40 the traveling rope from the gripping apparatus.

In the annexed drawings, forming a part of

this specification, Figure 1 is an end view of one form of my present gripping apparatus, showing the same in closed condition. Fig. 55 2 shows the same end view of the apparatus, the top roller of the same, however, being in contact with the releasing-rail, and the gripping-jaws are therefore separated from one another. Fig. 3 is an end view of another 60 form of the gripping apparatus. The gripping-jaws are shown in closed condition. Fig. 4 is a side view of this form of the apparatus, while Fig. 5 shows this apparatus in open condition. Figs. 6 and 7 are different 65 side views of a hanger provided at that construction of the gripping apparatus shown by Figs. 3 to 5, while Figs. 8 and 9 show two different side elevations of the trolley-frame of this latter apparatus. The wheels of the 70 trolley-frame are omitted.

In the construction shown by Figs. 1 and 2 the numeral 1 indicates the traveling rope, while 2 and 4 indicate the gripping-jaws, clamping the rope 1 between them when the 75 load is to be conveyed. The jaw 2 is formed integral with the trolley-frame 3, but may also be rigidly attached thereto. The other jaw 4 is provided at the top of the joint-piece 5, which by means of pivots 7 and 9 connects 80 the trolley-frame 3 with the suspension-frame 6 of the conveying vessel or the load. The numeral 8 denotes a fork formed integral with the frame 3 and containing the bolt 9. The numeral 10 denotes the fixed stationary 85 rail or cable on which the trolley-frame travels. As shown in Figs. 1 and 2, the bolt 9 is arranged at a distance from the vertical stationary rail 10, and for this reason the load has a tendency to turn the trolley-frame 3 in 90 the direction of the arrow 22 around the rail or cable 10, thereby forcing the gripping-jaw 2 toward the other jaw 4. If now the traveling rope passes through the space between both jaws, it will strongly be gripped by the 95 same, the force of this clamping action depending upon the weight of the load and the proportion of the distances of the rope 1 and the rail or cable 10 from the bolt 9. For the purpose to open the gripping apparatus and 100 release the whole carriage from the drawing action of the traveling rope 1 the trolley-frame 3 carries at its top a roller 11, loosely mounted on a vertical pivot 23 of the frame

3, such roller being adapted to travel along a rail 12, which is suitably provided in the station within which the carriage is to be emptied. This rail, which may be straight 5 or horizontally curved, is arranged in such a manner that the roller 11 touches the same when the trolley-frame 3 is still in the position shown in Fig. 1. While then the trolley-frame continues its travel it is successively turned by the rail 12 into the other position, (shown in Fig. 2,) thereby raising the bolt 9 and simultaneously lifting the load. During this time the jaw 4 maintains its vertical position, while, however, the jaw 2 makes 15 the same oscillatory movement as the trolley-frame 3. In consequence of this movement of the jaw 2 the apparatus is opened as much as required to entirely release the traveling rope 1. As the effective clamping action of 20 the apparatus is dependent upon the weight of the load and is always in a direct proportion thereto, the traveling rope is only gripped with the force required to draw the load with—that is to say, if the load is light the clamping 25 action of the apparatus is little—while a heavy load will produce a correspondingly stronger clamping action, so that even steep gradients of the ropeway can be overcome.

In the form of construction of the apparatus shown by Figs. 2 to 5 the rope 1 travels below the stationary cable or rail 10. For this reason the clamping-jaws must also be provided below this rail 10, and therefore the jaw 2 is arranged at the lower end of a 30 hanger 21, being by means of pivot 13 connected with the central vertical rib 20 of the trolley-frame. The hanger 21 is guided by two ribs 18 of the joint-piece 5, which also in this construction connects the suspension-frame 6 with the trolley-frame. To prevent the hanger 21 from leaving this guide, the bolt 7 passes through a vertical slot 17 of the hanger, the latter thus being kept down by the head of this bolt. The fork 8 and the 35 bolt 9 serve to connect the joint-piece 5 with the trolley-frame 3. At the lowermost part of the jaw 2 there is provided a fork by means of pivot 14 supporting the jaw 4, and this latter carries a lever 15, formed integral with 40 it. Through slots 19 of a fork forming the end of the said lever is passed a pivot 16, connecting the lower end of the joint-piece 5 with this lever. In this construction the gripping apparatus is closed and opened in quite 45 the same manner as described with reference to Figs. 1 and 2. The load turns the frame by means of the bolt 9 in one direction, thereby causing a small downward movement of the joint-piece 5. As, however, the bolt 13 is 50 arranged centrally within the trolley-frame, as will be seen from the drawings, this bolt is solely enabled to follow the frame 3 in its oscillatory movement; but it cannot make any remarkable vertical movement. In consequence 55 of this fact the aforesaid downward movement of the lever 15 will cause the required approximation of the jaw 4 toward the

jaw 2, whereby the traveling rope is strongly gripped.

When the gripping apparatus is to be opened, the roller 11 of the trolley-frame 3 is brought in contact with a rail 12, constructed and arranged in quite the same manner as described with reference to Figs. 1 and 2. The trolley-frame will therefore also receive 75 an oscillatory movement contrary to the direction in which the load tends to move it, whereby the joint-piece 5, and with it the load, are raised in the required degree to separate the jaw 4 from the jaw 2, so that the traveling rope will be totally freed from the clamping action, as shown in Fig. 5.

Having now particularly described and ascertained the nature of my said invention and in what manner the same is to be performed, I declare that what I claim is—

1. A gripping apparatus for aerial ropeways, comprising a trolley-frame, a pivot provided at a distance aside from the said trolley-frame, a joint-piece, supported by such pivot, a load-suspension frame, hinged to said joint-piece, a pair of clamping-jaws, so arranged as to be closed and opened by an oscillatory movement of the trolley-frame transverse to the stationary cable or rail, supporting such frame, a roller loosely mounted on a pivot, provided at the upper part of the trolley-frame, a rail, provided to come in contact with said roller and forming in the ground-plane an acute angle with the stationary cable or rail, substantially as set forth.

2. A gripping apparatus for aerial ropeways, comprising a trolley-frame, a pivot, provided at a distance aside from said trolley-frame, a joint-piece, supported by such pivot, a load-suspension frame hinged to said joint-piece, a pair of clamping-jaws, the one being securely connected with the trolley-frame, while the other forms a part of the joint-piece, such clamping-jaws being so arranged, as to be approximated toward each other by an oscillatory movement of the trolley-frame transverse to the stationary cable or rail, supporting such frame, a roller, loosely mounted on a pivot, provided at the upper part of the trolley-frame, a rail provided to come in contact with said roller and forming in the ground-plane an acute angle with the stationary cable or rail, substantially as set forth.

3. A trolley-frame for aerial ropeways, comprising a hinge part at the outside of one side part, a rib provided between the front and rear pivot-eyes of the wheel-axles and connecting both side parts of the frame, an eye, provided at the lower part of said rib, a pivot provided at the upper part of the frame, arranged vertically and adapted to carry a roller, substantially as set forth.

4. In an aerial ropeway, the combination of an elevated guide or support, a trolley mounted to travel on said support, a suspension-frame pivotally connected to the trolley to permit the latter to vibrate transversely of said support, a traction-cable, a clamping-

jaw connected to the trolley and movable vertically between guides on the suspension-frame, and a second clamping-jaw connected to the suspension-frame.

5 5. In an aerial ropeway, the combination of an elevated guide or support, a trolley mounted to travel on said support, a suspension device mounted upon a pivot at one side of the trolley and permitting the trolley-frame to vibrate transversely of said guide or support, a traction-cable, a clamping-jaw connected to the trolley and arranged at one side of the traction-cable, and a second clamping-jaw connected to the suspension-frame.

10 6. In an aerial ropeway, the combination of an elevated guide or support, a trolley mounted to travel on said support, a traction-cable, a cable-clamping jaw connected to the

trolley-frame, a suspension-frame connected to the trolley-frame and permitting the latter 20 to vibrate transversely of the guide or support, a second clamping-jaw carried by said suspension-frame, an abutment, 12, at one side of the trolley-frame, and means connected to the trolley-frame and adapted to contact 25 with said abutment to rock the trolley-frame transversely of its support or guide to release the trolley and suspension-frame from the traction-cable.

In testimony whereof I affix my signature 30 in presence of two witnesses.

WILHELM EICHNER.
